GRIP LOCATOR FOR A TENNIS RACQUET

Hector O. Conde, Richmond, and Jose G. Vidal, Kensington, Calif., assignors to Electronic Protection Systems

Filed Apr. 8, 1974, Ser. No. 458,556

Term of patent 14 years

Int. Cl. D21—02

U.S. Cl. D34—5 ST

FIG. 3

FIG. 2

FIG. 1

FIG. 4

FIG. 5

FIG. 6

FIG. 1 is a side elevational view of the grip locator for a tennis racquet showing our new design.

FIG. 2 is a front elevational view thereof.

FIG. 3 is a top plan view thereof.

FIG. 4 is a rear elevational view thereof.

FIG. 5 is a bottom view thereof.

FIG. 6 is an elevational view of the side opposite FIG. 1.

We claim:

The ornamental design for a grip locator for a tennis racquet, as shown.
